UNITED STATES PATENT OFFICE.

LEVI MALUGEN, OF CENTERVILLE, TENNESSEE, ASSIGNOR OF ONE-HALF
TO ALLISON H. LEATHERS, OF DICKSON, TENNESSEE.

ENGINE.

No. 853,252.

Specification of Letters Patent.

Patented May 14, 1907.

Application filed January 22, 1907. Serial No. 353,497.

To all whom it may concern:

Be it known that I, LEVI MALUGEN, a citizen of the United States, residing at Centerville, in the county of Hickman and State of Tennessee, have invented a new and useful Engine, of which the following is a specification.

This invention relates to reciprocating piston engines of the type wherein opposed pistons are employed, and the object is to provide for economy in the use of the motive agent, whether it be steam, compressed air, or other agent, by utilizing extensively the expansive force of the motive agent, while insuring the direct application of the agent to the piston head at the commencement of the power stroke, the opposed piston heads at that point being in close proximity so as to avoid waste of pressure necessary to properly charge the previously exhausted space. To accomplish this it is proposed to so arrange and connect the pistons, two of which constitute the heads of the cylinder, as to produce a cylinder of varying length, the length being increased during the power stroke to the fullest capacity to give opportunity for complete expansion and then being shortened by the inward movement of the cylinder piston, which is at the main inlet end of the cylinder, to shorten what may be termed the operative end of the cylinder prior to the inlet of the motive agent.

Further objects and advantages of the invention will appear in the following description, it being understood that various changes in the form, proportions and minor details of construction may be resorted to without departing from the spirit or sacrificing any of the advantages of the invention.

In the drawings:—Figure 1 is a plan view showing one embodiment of the invention. Fig. 2 is a longitudinal sectional view of the same. Figs. 3, 4, 5 and 6 are diagrams showing the different stages of the piston stroke.

Similar reference characters indicate corresponding parts of the several figures.

In the cylinder 1 are arranged what shall for convenience be termed the cylinder head pistons 2 and 3 and the intermediate piston 4, the piston rod 5 of the intermediate piston extending through a stuffing box 6 in the cylinder head piston 2. In the construction illustrated the cranks 7 and 8, are arranged on quarters and are connected, respectively,

with the piston rod of the intermediate piston, and with the piston rod frame 9 of the cylinder head pistons by means of pitmen 10 and 11. The piston rod frame consists of connected cross heads 12 from which extend rods 13 to the cylinder head piston 2, and rods 14 extending through guides 15 and connected to a cross head 16 which in turn carries the rod 17 of the cylinder head piston 3. Thus the cylinder head pistons are connected for simultaneous movement in the same direction, although obviously the movements of the cylinder head pistons under all conditions will be in opposite directions with reference to the cylinder, inasmuch as the inward movement of one of the cylinder head pistons tending to shorten the cylinder will be accomplished during the outward movement of the other cylinder head piston tending to lengthen the operative portion of the cylinder.

As soon as the piston rods are in the position indicated in Fig. 1 in position to take the steam through cylinder port 18 controlled by the slide valve 19, which may be operated by any suitable mechanism, not specifically illustrated, the first operation due to the inlet of the steam (or of the motive agent) will be to advance the intermediate piston which is just in position to commence the power stroke, inasmuch as the crank to which it is connected has passed the dead center and has made about a one-eighth revolution (see Figs. 2 and 3), while the cylinder head pistons being connected with the crank which has completed the power portion of its stroke and is about to pass the dead center, will remain approximately stationary. Of course, in practice there will be some motion of these cylinder head pistons during this portion of the stroke, but the motion will be comparatively small and, therefore, substantially negligible for the purposes of this explanation. The intermediate piston will advance for approximately one-half of its stroke, (although this distance may be varied to suit the conditions of load and otherwise under which the engine is operated), when by suitable mechanism (not shown), the steam should be cut off to permit operation under expansion. Assuming that at this point in the progress of the mechanism the cranks to which the cylinder head pistons are connected has passed the dead center and are about to

commence the power portion of their stroke (Fig. 4), the intermediate piston will continue to move in the direction indicated by the arrow in Figs. 1 and 4 and in the direction in 5 which it commenced to move as above stated, while the cylinder head pistons will commence to move in the opposite direction so that the cylinder head piston toward which the intermediate piston is moving will 10 move toward the intermediate piston, and thus rapidly reduce the exhausting space, while the cylinder head piston from which the intermediate piston is traveling will recede under the expansive force of the steam 15 to the full limit of the capacity of the cylinder. When the intermediate piston has reached the limit of its advance movement and has met the cylinder head piston toward which it was traveling, it will commence a 20 backward or retro-grade movement followed by the cylinder head piston toward which it has been advancing, while the cylinder head piston from which the intermediate piston had been receding continues to exert power 25 under the expansive force of the steam acting thereon, this motion continuing until the cylinder head piston which is adjacent to the intermediate piston has advanced sufficiently to cause registration of the space between 30 said pistons and the cylinder port 20, whereupon the operation of the parts will be repeated in the reverse direction to that above described.

The advantage of this construction is that 35 while the cylinder head piston which has been acting under the expansive force of the steam has traveled to the full limit of the cylinder so as to utilize the expansive force effectively, the other cylinder head piston 40 which is about to receive the effect of the motive agent due to the fact that the intermediate piston is in proximity thereto has moved inward so that on the inlet of the motive agent there is no considerable cylinder 45 space to be filled before the motive agent has its desired effect upon the intermediate piston and the intermediate piston has moved to such an extent that its effect upon the crank or other connection is about to commence 50 the power stroke, or that portion of its travel which is the most effective in moving the load. The cylinder head pistons and the intermediate piston operate alternately at their greatest efficiency.

55 It will be noted that the distance between

the two ports 18 and 20 is less than the length of the stroke of the intermediate piston 4, so that the ports are in part controlled by said piston, and the valve may be opened full while the pistons are in the positions 60 shown in Fig. 5, for instance, and steam, or other actuating fluid cannot enter until the pistons have moved to the positions shown in Fig. 6, where there will be a full port opening, and the steam will quickly fill the small 65 space between the two pistons.

I claim:—

1. In an engine, a crank shaft having a pair of cranks, a ported cylinder, a pair of cylinder head pistons connected to each other and to one of the cranks, and an intermediate piston connected to the other crank, the distance between the cylinder ports being less than the stroke of the intermediate piston, and the crank connections being arranged to 70 permit movement of the pistons alternately in the same and in opposite directions.

2. The combination in an engine, of a crank shaft having a pair of cranks, a ported cylinder, a pair of cylinder head pistons rigidly connected to each other and to one of the cranks, and an intermediate piston connected to the other crank, the inner ends of the cylinder ports being under the control of the intermediate piston and being arranged 80 at a distance from each other less than the stroke of such intermediate piston, a steam chest provided with an exhaust port, the cylinder ports also communicating with the steam chest, and a valve arranged in said 85 steam chest for controlling said ports.

3. An engine having a crank shaft, and a pair of cranks, a cylinder provided with intermediate cylinder ports, a pair of cylinder head pistons connected to each other and to 90 one of the cranks, an intermediate piston connected to the other crank, the stroke of the intermediate piston being greater than the distance between said cylinder ports, the crank connections of the pistons being arranged 95 to transmit movement to the crank shaft alternately from the intermediate piston, and one of the cylinder head pistons.

In testimony that I claim the foregoing as my own, I have hereto affixed my signature 100 in the presence of two witnesses:

LEVI MALUGEN.
